(57) **CLAIM**

The ornamental design for a pump body for a breast pump, as shown and described.

DESCRIPTION

FIG. 1 is a perspective view of an embodiment of the pump body for a breast pump;

FIG. 2 is a front elevation view of the embodiment of the pump body for a breast pump shown in FIG. 1;

FIG. 3 is a back elevation view of the embodiment of the pump body for a breast pump shown in FIG. 1;

FIG. 4 is top plan view of the embodiment of the pump body for a breast pump shown in FIG. 1;

FIG. 5 is a bottom plan view of the pump body for a breast pump embodiment shown in FIG. 1;

FIG. 6 is a side elevation view of the embodiment of the pump body for a breast pump shown in FIG. 1; and,

FIG. 7 is an opposite side elevation view of the embodiment of the pump body for a breast pump shown in FIG. 1.

The broken lines in the drawings represent environmental subject matter and form no part of the claimed design.
